UNITED STATES PATENT OFFICE.

JOHN THOMAS LENOIR, OF COLUMBIA, ASSIGNOR OF ONE-HALF TO BUFORD
A. SUMMER, OF BUFORD, MISSISSIPPI.

WASH-BOARD.

SPECIFICATION forming part of Letters Patent No. 451,432, dated April 28, 1891.

Application filed September 10, 1890. Serial No. 364,531. (No model.)

To all whom it may concern:

Be it known that I, JOHN THOMAS LENOIR, of Columbia, in the county of Marion and State of Mississippi, have invented a new and 5 useful Improvement in Wash-Boards, of which the following is a full, clear, and exact description.

This invention relates to an improved wash-board whereon fibrous material is manually 10 rubbed to remove dirt and stains, and has for its object to provide an improved device of the type mentioned, which is of simple construction, and that will afford means for a renewal of the rubbing-surfaces by a change 15 of adjustment of its parts.

To this end my invention consists in the construction of parts and their combination, as hereinafter described, and indicated in the claims.

20 Reference is to be had to the accompanying drawings, forming a part of this specification, in which similar letters of reference indicate corresponding parts in all the figures.

Figure 1 is a plan view of the wash-board. 25 Fig. 2 is a longitudinal section of the same, taken on the line 2 2 in Fig. 1. Fig. 3 is a side view of a modified form of the detachable rubber-bars. Fig. 4 is a side view of the same in the direction of the arrow in Fig. 3; 30 and Fig. 5 is a transverse section of the same, taken on the line 5 5 in Fig. 3.

The wash-board consists, essentially, of a series of independent rubber-bars A, which are arranged in contact with each other and all 35 held assembled by two side bars B, so as to produce a rubbing-surface at the top and bottom of the device. The rubber-bars and side bars are preferably made of hard wood. One form of the rubber-bars is shown in Figs. 1 40 and 2, and as all of said bars therein illustrated are alike the description of one bar will suffice for the series.

As more plainly shown in Fig. 2, each rubber-bar A consists of a pair of rectangular 45 strips a, of suitable width and thickness and equal length, which latter represents the width of the wash-board between the side bars B. The two similar strips a are retained spaced apart a proper distance parallel to 50 each other by the blocks b. Said blocks,

being secured near the ends of the strips a, have their ends projected beyond the ends of said strips, the projecting portions b' having equally reduced rounded bodies, as shown in Fig. 1. The side bars B are of equal 55 dimensions and like form, each consisting of a flattened bar having parallel side faces and edges, handles d being formed on the ends of said bars for convenience in handling the board and to avoid taking up room in the 60 wash-tub when the device is in use. Aligning similar longitudinal slots e are formed in the side bars B near their transverse centers and extend a suitable length from points equally distant from the ends of the handles 65 d, said slots having a width sufficient to permit the insertion therein of the rounded ends b' of the blocks b.

If desired, each of the rounded portions b' of the spacing-blocks b may be extended a 70 sufficient distance through the slotted side bars B and threaded to receive nuts c on their projecting ends, as shown in Fig. 1, or the spacing-blocks of alternating rubber-bars may be projected and threaded to receive binding-nuts, so that the entire series of rubber-bars 75 will be held securely attached to the side bars.

As shown in Fig. 2, the rubber-bars A are so arranged in succession that one of the strips a will have close contact with a similar strip on the adjoining rubber-bar, all 80 said rubber-bars having the same inclination from the plane of the parallel edges of the side bars B, which will project similar angular corners a' on each strip a above the other 85 corners of said strips, and thus afford rubbing-surfaces on each side of the board of the conventional angular form of ribs.

There being slots g between the strips a of each rubber-bar A, in using the wash-board 90 the water from the clothes or other material operated upon will circulate freely through the board and be prevented from splashing upwardly upon the person of the operator.

The strips a should be attached to the blocks 95 b in a manner which will permit them to be altered in position. Dowel-pins, such as are shown by dotted lines at h in Fig. 3, may be utilized to removably secure the strips and blocks together, whereby the unused angular 100

lar corners a' of the strips a may be located in suitable positions for use as rubbing-surfaces for the wash-board.

When rubber-bars A are each provided with two strips a , it will be evident that there will be four corners on each strip which are available for rubbing-faces on the board. The alteration of adjustment necessary to bring said corners into position being obvious, need not be detailed.

In the rubber-bar A' shown in Figs. 3, 4, and 5 the only alteration from the form shown in Figs. 1 and 2 consists in the provision of four strips i in place of two strips a , said strips i being arranged in pairs oppositely on the spacing-blocks b and removably attached thereto by the dowels h , so that by turning the strips i sidewise and renewing their attachment to the blocks b an increased number of new rubbing-faces may be provided for the wash-board.

Having thus described my invention, what

I claim as new, and desire to secure by Letters Patent, is—

1. A rubber-bar for wash-boards, consisting of rectangular strips and spacing-blocks, to which the strips are removably attached near their ends, the spacing-blocks having threaded outer ends, substantially as shown and described, for the purpose set forth. 25

2. In a wash-board, the combination, with a pair of longitudinally-slotted side bars, of a series of independent transverse rubber-bars, each consisting of rectangular strips and spacing-blocks, to which the strips are 30 removably attached near their ends, the spacing-blocks having rounded and threaded extremities projecting through the slots in the side bars and provided with binding-nuts, substantially as shown and described.

JOHN THOMAS LENOIR.
